UNITED STATES PATENT OFFICE

EUGENE OSCAR ENGELS, OF SAGINAW, MICHIGAN, ASSIGNOR TO BAKER PERKINS COMPANY, INC., OF SAGINAW, MICHIGAN, A CORPORATION OF NEW YORK

HEATING SYSTEM FOR BAKE OVENS

Application filed September 11, 1930, Serial No. 481,112. Renewed August 20, 1931.

This invention relates to bake ovens heated by circulating hot gases from a furnace through radiating flues in the baking chamber and back through the furnace, venting off enough of the gases of combustion to balance the intake of air necessary for combustion.

The object of my invention is to provide a bake-oven heating system of this type where-
10 in a sub-atmospheric pressure of the hot gases is established and maintained within the radiating flues or flue radiator, and the furnace. Keeping the pressure of the gases circu-
15 lating within such a closed circuit slightly below that of the atmosphere presents the fol-
lowing advantages:

First, if leaks develop in the radiating flues, the leakage will be from the baking chamber into the flues, instead of from the flues out-
20 ward into the baking chamber. Thus smoke and soot are kept out of the baking atmos-
phere and prevented from coming into contact with the goods being baked.

Second, it makes easier the lighting of the
25 pilot and main burner if gas or oil is used as fuel, since it eliminates back pressure in the furnace at the fuel nozzles. The burner equipment is simplified, since the suction draws the combustion air into the furnace,
30 and it may also draw in the gas, if gas is used for fuel. In the latter case gas or air com-
pressors may be dispensed with.

The oven heating system to which my in-
35 vention is applied comprises essentially a fur-
nace, a series of flues, referred to hereafter as a radiator, supply and return conduits con-
necting the radiator with the combustion chamber of the furnace in a continuous closed circuit, and a gas impeller in the circuit for circu-
40 lating the heated gases from the furnace, through the radiator and back to the furnace.

To a system of the type just described above is added the improvement constituting my in-
45 vention, namely, an exhauster for maintain-
ing a sub-atmospheric pressure throughout the furnace, the combustion chamber, the sup-
ply conduits, and the radiator system. The
50 gas that this exhauster discharges from the enclosed circuit is replaced by fresh air to

support combustion drawn into the furnace through a restricted duct or opening.

A preferred embodiment of my invention is illustrated in the accompanying drawings,
55 of which:

Fig. 1 is an isometric view, showing dia-
grammatically a complete operating assem-
bly as employed to heat a single-lap travel-
ing tray oven.

Fig. 2 is a fragmentary longitudinal sec-
tion of the fuel burner and the furnace—taken
60 along line 3—3 of Fig. 1.

Referring to Fig. 1, numeral 1 designates
the outline of the oven. For purposes of il-
lustration I have shown a heating system in-
65 stalled in a traveling tray oven, but it is
equally applicable to an oven of any other
type. The furnace 2 is provided with a
gas or oil burner 3 of any suitable type. The
combustion air is drawn in by suction through
70 an inlet pipe 4. The inlet 4 is so restricted
in capacity that even when the minimum vol-
ume of gases is being discharged from the
circulating system the desired condition of
partial vacuum will be maintained in the
75 furnace. This restriction may be accom-
plished by limiting the size of the inlet, in
which case the quantity of combustion air
drawn in will be adjusted by increasing or
decreasing the volume of gas vented out of
80 the system. In this case the permanent open-
ing will be small enough to maintain the
desired degree of suction when the burner is
operating at its lowest rate. It is preferable,
however, to vent out of the circulating sys-
85 tem the minimum volume of gas necessary to
maintain the partial vacuum and to recir-
culate as much of the gases as possible. To
make this possible the restriction of inlet 4
is provided by an adjustable damper or
90 valve 5. I have found that a gaseous or va-
porized fuel burner is preferable for use in
this system, but a furnace for burning solid
fuel may be employed if desired and is in-
95 tended to come within the scope of the ap-
pended claims.

From the furnace the hot gases of combus-
tion are led through a supply conduit 6 to
the inlet header 7a of a flue radiator 7. One
100 or more of these flue radiators are installed

within the baking chamber of the oven, depending upon its size. The form of these radiators will vary with the design of the individual ovens to which they may be applied, and is immaterial to the invention. The form which I have illustrated comprises an inlet and an outlet header, 7a and 7c respectively, connected by radiator flues 7b. The hot gas gives up its heat as it passes through the radiator, and then is discharged from the exhaust header 7c into a return conduit 8. The conduit 8 collects the cool gases from all of the exhaust headers and returns it to the combustion chamber of the furnace (see Fig. 2).

Circulation of the combustion gases through the closed circuit just described is maintained by any suitable gas impeller, such as a fan 9 driven by motor 10. The fan 9 is preferably located in the cool gas return conduit 8, but may be placed elsewhere in the system, when a separate exhauster independent of fan 9 is used to positively induce a sub-atmospheric pressure within the system.

The sub-atmospheric pressure within the heating system can be maintained by either of two forms of exhauster; first, by a positively acting exhauster independent of the gas-circulating impeller, and second, by providing a suitable vent from the duct system located in the high-pressure zone just in front of the circulating impeller. With either of the above means the supply of fresh air to the furnace is restricted so that throughout the range of heat production a greater volume of air will be vented off than is drawn into the furnace.

A preferred form of the first mentioned positive exhauster will now be described. Referring to Fig. 1, an aperture 11 in conduit 8 opens into an exhaust conduit 17, which communicates with the inlet to an exhaust fan 14, driven by a motor 15. A damper 12 controls the volume of gas drawn through conduit 13. The fan 14 is preferably arranged to exhaust the gas through a stack to the atmosphere.

While it is not essential to the successful maintenance of a sub-atmospheric pressure in the furnace and radiators that the fan be connected to the circuit at any particular point, it is preferable from a mechanical view point to locate it as shown in Fig. 1, communicating with conduit 8 at a point between the circulating fan 9 and the furnace 2. Here the fan handles the gases at their coolest, after they have passed through the flue radiators 7. The fan also requires less power at this point than elsewhere, since the pressure of the gases is highest just ahead of the fan 9.

The second means for producing and maintaining the desired sub-atmospheric pressure in the heating system consists in a vent

exhausting from the duct system located just ahead of the gas impeller. Referring to Fig. 1, the exhaust fan 14 is omitted, and the exhaust pipe 13 is caused to discharge directly to the atmosphere through a suitable stack 70 (not shown). The aperture 11 into pipe 13 from conduit 8 then constitutes the vent, mentioned above, and the gas discharged from the circulating fan 9 will tend to flow out of the system through the vent. I have discovered that a plus pressure may exist in front of the fan 9 simultaneously with a minus pressure in the furnace and the subsequent portions of the system, without the use of any dampers or other special flow-impeding devices. By suitably proportioning the size and length of conduit 8, the size of the vent aperture 11, and the normal flow of fuel and air to the furnace, to the capacity of the fan, the system can be readily made to operate inherently according to the principle of the invention. 75

To permit of the adjustment of the system to varying heating demands, adjustable dampers and valves have been provided as follows: A valve or damper 16 in conduit 8 between the exhaust opening 11 and the furnace 2 can be adjusted to produce any desired degree of pressure behind it. By adjusting this damper 16 and the exhaust-pipe valve 90 12 the proportion between the volume of gas exhausted and the volume of gas recirculated may be altered as desired. If the valve 16 should be closed all the way and valve 12 opened, a maximum of gas will be discharged through the exhaust pipe and none will be recirculated. 95

Using either of the above-described suction-producing systems, dampers 12 and 16 will be adjusted to vent off the amount of gases required to produce the desired minus pressure in the furnace and radiating flues. Their setting will depend upon the volume of fresh air admitted through inlet 4 and the amount of fuel being admitted to the burner 3, and they will be adjusted so that the volume of gas exhausted from the system is enough greater than the volume of fresh air and fuel gas drawn into the furnace through inlet pipe 4 to reduce the pressure of gases within the furnace 2, the supply conduit 6, and the flue radiator 7 slightly below that of the atmosphere. 100

A fresh air intake opening 17, controlled by a valve 18, is installed in conduit 8 beyond the damper 16. By closing damper 16, opening damper 12, and running the circulating fan 9 with valve 18 open, fresh air will be drawn into the system and circulated through the furnace 2, the conduits 6, 8 and radiator system 7. This is done before lighting up the furnace to insure that no explosive gases will be present in the system. This ventilating operation may also be used to reduce the oven temperature quickly when desired. 110 115 120 125

Having thus described my invention, what I claim and desire to secure by Letters Patent is:

1. In combination a bake oven having a flue radiator therein, a furnace having a gas-air burner, conduits connecting the combustion chamber of the furnace with the radiator in continuous closed circuit, a gas impeller located within said closed circuit and power-driven, an exhaust fan operative independently of said impeller and having its intake side in communication with said circuit between the outlet of said radiator and the inlet to said furnace, for maintaining pressure less than atmospheric within the radiator and within the furnace chamber, said exhaust fan arranged to discharge outside of said circuit.

2. In combination a bake oven having a radiator therein, a furnace, conduits connecting said radiator with the combustion chamber of said furnace in continuous closed circuit, a gas impeller located within said closed circuit, an exhauster in communication with said circuit and a restricted fresh air inlet to said furnace of size so proportioned to the capacity of said exhauster that the pressure within said radiator and furnace is maintained at less than that of the atmosphere when said furnace and exhauster are in operation.

3. In combination, a bake oven having a flue radiator therein, a furnace having a fuel-air burner, a restricted combustion air inlet to said furnace, conduits connecting the combustion chamber of said furnace with the radiator in continuous closed circuit, a power-driven gas impeller within said closed circuit to maintain continuous circulation of gases of combustion through the circuit, and a valved gas vent to the atmosphere from said circuit located between the pressure side of said impeller and said furnace, adapted to vent off a volume of gas larger than the volume of air entering the furnace to maintain a sub-atmospheric pressure in that part of the circuit which includes said furnace and said radiator.

4. In combination, a bake oven having a flue radiator therein, a furnace, a valve-controlled air inlet to said furnace, conduits connecting said furnace with said radiator in continuous closed circuit, a gas impeller within said closed circuit to maintain continuous circulation of the gases of combustion through said circuit, and means for discharging gases from said circuit to the atmosphere in such quantity as to maintain a sub-atmospheric pressure in that portion of said circuit including said furnace and said flue radiator.

In testimony whereof, I affix my signature.
EUGENE OSCAR ENGELS.
